UNITED STATES PATENT OFFICE

LORAN F. DOEN, OF CLEVELAND, OHIO, ASSIGNOR TO THE CLEVELAND HEATER COMPANY, OF CLEVELAND, OHIO, A CORPORATION OF OHIO

VALVE

Application filed April 15, 1927. Serial No. 184,142.

This invention relates to gas burning appliances and in particular the means for controlling the flow of gaseous fuel in such appliances.

5 It has for its object the provision of an adjustable needle valve that provides a means for readily and easily attaching and detaching the gas line to an appliance.

10 A further object of this invention is to provide a valve that is simple in construction and comprises a relatively small number of inexpensive and rugged elements.

15 Another object of this invention is to provide a valve with a union connection between its inlet and outlet portions.

In certain types of gas burning appliances such as storage automatic water heaters, the flow of gaseous fuel to the main heating burner is controlled by a thermostatic or 20 other type of automatic valve. An adjusting valve is usually placed in the feed line between the automatic valve and the burner and is commonly secured to the mixing or Venturi tube of the burner. The gas supply 25 conduit is usually secured to the thermostatic valve by means of a union connection and the above cited fittings connected to each other and then to the burner without the use of a second union connection. It is apparent that 30 such an arrangement necessitates considerable labor when it is desired to remove the heater from the storage tank or the burner from the heater and it is the overcoming of these and other objections that my invention 35 is particularly directed to.

The drawing illustrates a sectional elevation of a form of my improved combined needle valve and union.

The valve comprises a valve body 1 having 40 an inlet portion 2 externally threaded to receive a gas conduit, and an outlet portion 3 externally threaded to receive a union nut 4 which serves to detachably secure a union outlet spud carrier 5 to the valve body. The 45 face 14 of the spud carrier, which is in contact with the valve body, is spherical in contour and is adapted to form a gas tight contact with a similarly faced portion of the valve body 1.

50 The spud carrier 5 is externally threaded

at 12 to be secured to the appliance and is provided with a lock nut 11 to securely hold the spud carrier 5 in the desired position. The spud carrier 5 is internally threaded at 13 to receive the spud 6 which is provided with the gas passage 7 which constitutes a restricted outlet passage for the valve. The flow of gas through the passage 7 is controlled by an adjustable needle valve 8 which is threadably received in a suitable opening 9 in 55 the valve body 1.

A closure cap 10 is provided to prevent the escape of gas from the valve body at the point where it receives the needle valve 8.

Furthermore it is to be understood that the 60 particular forms of apparatus shown and described and the particular procedure set forth are presented for purposes of explanation and illustration and that various modifications of said forms and procedure can be 65 made without departing from my invention 70 as defined in the appended claims.

What I claim is:

1. In an adjusting valve for gas burning 75 appliances, a valve body provided with inlet and outlet openings, a spud carrier, a union connection between said spud carrier and the outlet end of said valve body, a spud carried by said spud carrier and an adjustable needle to vary the size of the opening at the inlet end of said spud.

2. A needle adjustment regulating valve comprising, a valve body provided with inlet and outlet passages, a coupling member having a restricted outlet passage, and means 85 comprising a union connection to detachably secure said coupling member to the outlet end of said valve body, and an adjustable needle valve cooperating with said coupling member to regulate fluid flow therethrough. 90

3. A regulating valve comprising a valve body having inlet and outlet passages, a spud carrier having securing means at one end and adapted to be detachably secured at its opposite end to the outlet end of the valve body, a spud carried by said spud carrier, and an adjustable needle carried by said valve body to regulate fluid flow through 95 said spud.

4. A reducing valve for gas burning ap- 100

pliances having an enlarged inlet and a restricted outlet passage, an adjustable valve member operatively associated with said restricted outlet passage for regulating fluid flow therethrough, threaded portions formed on said valve for attaching said valve to a gas supply conduit and a gas burning appliance, and means independent of said threaded portions provided in said valve for disconnecting the appliance from the gas supply conduit at a point intermediate said threaded portions.

- 10 5. An angle valve having a union outlet, a readily removable reducing spud adapted for reception in said union outlet, and an adjustable needle cooperating with said spud to regulate fluid flow therethrough.

In testimony whereof I affix my signature.
LORAN F. DOEN.
